UNITED STATES PATENT OFFICE.

FREDERIC D. BLAUVELT, OF MONTCLAIR, NEW JERSEY.

DESIGN FOR A PLUMBER'S TRAP.

Application filed March 30, 1926. Serial No. 17,121. Term of patent 3½ years.

To all whom it may concern:

Be it known that I, FREDERIC D. BLAUVELT, a citizen of the United States, residing at Montclair, in the county of Essex and State of New Jersey, have invented a new, original, and ornamental Design for a Plumber's Trap, of which the following description, in connection with the accompanying drawing, is a specification.

Fig. 1 is a side view of a plumber's trap embodying the design;

Fig. 2 is a view looking from the left of Fig. 1;

Fig. 3 is a view looking from the right of Fig. 1;

Fig. 4 is a top plan view; and
Fig. 5 is a bottom plan view.

I claim:

The ornamental design for a plumber's trap as shown.

FREDERIC D. BLAUVELT.
